UNITED STATES PATENT OFFICE.

WILLIAM R. KINNEAR, OF COLUMBUS, OHIO.

DESIGN FOR A CEILING.

SPECIFICATION forming part of Design No. 19,755, dated April 8, 1890.

Application filed February 20, 1890. Serial No. 341,223. Term of patent 3½ years.

To all whom it may concern:

Be it known that I, WILLIAM R. KINNEAR, of Columbus, in the county of Franklin and State of Ohio, have invented a new and original Design for a Ceiling; and I do hereby declare the following to be a full, clear, and exact description of the same, reference being had to the accompanying drawing, forming a part of this specification, and to the figures and letters of reference marked thereon.

This invention relates to designs for ceilings and more especially for paneled ceilings.

In the drawing, the figure is a plan view of a section of a ceiling embodying this design.

Heretofore ceilings have been divided into panels by raised stiles or moldings. These stiles and moldings have abutted at an angle which has produced an appearance of heaviness and stiffness in the work, which it is the object of this design to obviate.

In the drawings, the letters A designate the stiles which divide the ceiling into panels, the

letters B the junction of the said stiles, the letters C rosettes mounted on the said junctions, and the letters D the moldings on the 25 sides of the stiles.

The design consists in the curved lines of the edges of the stiles near the junctions B, which form at these points a boss-like configuration with curved sides, into which the 30 stiles appear to merge.

The characteristic feature of the design is the boss-like configuration at the junction of the stiles at the point of junction, which is produced by the curved-edge lines of the stiles, 35 as set forth and shown in the drawing.

What I claim is—

The design for ceilings, substantially as herein shown and described.

WILLIAM R. KINNEAR.
